I. H. ERB

HEATING AND COOLING SYSTEM FOR WINDOWS, DOORS, AND THE LIKE

Filed Sept. 22, 1922

Patented Aug. 21, 1923.

1,465,513

UNITED STATES PATENT OFFICE.

IRWIN H. ERB, OF WEST LIBERTY, IOWA.

HEATING AND COOLING SYSTEM FOR WINDOWS, DOORS, AND THE LIKE.

Application filed September 22, 1922. Serial No. 589,909.

To all whom it may concern:

Be it known that I, IRWIN H. ERB, a citizen of the United States, and a resident of West Liberty, in the county of Muscatine and State of Iowa, have invented a certain new and useful Heating and Cooling System for Windows, Doors, and the like, of which the following is a specification.

The object of my invention is to provide a heating and cooling system for windows, doors and the like, particularly designed for warming or cooling the air that passes into a building around a window or door and for supplying cool or warm air, as may be desired, adjacent to the joints around a window or door.

With this and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 shows an interior or front elevation of a window equipped with a heating and cooling system embodying my invention.

Figure 2 is a horizontal, sectional view taken on the line 2—2 of Figure 1.

Figure 3 is a vertical, sectional view taken on the line 3—3 of Figure 1, the lower window sash being closed; and

Figure 4 is a horizontal, sectional view taken on the line 4—4 of Figure 3.

In general, it may be said that my invention consists in providing in connection with the ordinary frame around a door or window a secondary frame made of tubular material, arranged to afford a stop for the door or window supported in the ordinary frame, and adapted to serve as an air conducting means.

In the accompanying drawings, I have illustrated my invention in connection with a window having two sashes.

In the drawings, I have used the reference numeral 10 to indicate generally the ordinary frame of the window, having the stool 11 and the sill 12.

Slidably mounted on the main frame 10 and arranged to pass each other in the ordinary way are upper and lower window sashes 13 and 14.

My secondary frame consists of tubular members forming stops between the two

sashes. The secondary frame has a top member 15, side members 16 communicating therewith and bottom members 17, extending toward each other from the side members 16 to the middle of the window at the bottom thereof.

The adjacent ends of the members 17 may communicate with downwardly projecting members 18 and 19. One of the members 18 or 19 may be connected with a suitable source of hot air supply or a suitable source of cold air supply and the other member 18 or 19 may be connected in anyway for providing circulation of hot or cold air.

The members 16 form upright parting strips between the sashes 13 and 14 and thus form a part of the window frame installation.

The member 15 forms a parting strip for the inside of the upper sash and for the outside of the lower sash when the latter is raised. Similarly the members 17 form parting strips for the upper and lower sashes.

The members 16 may be connected midway between the top and bottom of the window by means of a cross member 20.

It will be understood that the members of the secondary frame are connected together for affording a circulation of air entirely around the main window frame.

For instance, after hot or cold air is supplied through the member 19, it will pass through the right-hand member 17 thence upwardly through the right-hand member 16 across to the other member 16 through the members 20 and 15 and thence downwardly to the other member 17 and the member 18.

The members 17 are preferably inset in the sill 12, as shown in Figure 3.

On their inside faces, the members 17 are provided near their upper portions with one or more openings 22 for allowing the exit of air.

Similarly, the inner faces of the lower edges of the members 16 are provided with openings 23. The member 20 is provided with one or more openings 24 on its inner face.

The upper portions of the members 16 and the member 15 are provided in their outer faces adjacent to the sash 13 with one or more openings 25.

The openings 22, 23, 24 and 25 are intended to be conveniently located, so as to be ad-

ja cent to the path of travel of incoming air, which may pass around the window sashes into a room.

When my invention is installed and the

5 weather is cold, hot air is supplied to the member 19 and passes around the secondary frame and some of the hot air escapes and mingles with incoming air around the window frame.

10 It is well-known that many devices have been provided for making tight joints around window or door frames. One objection to such devices is that it is ordinarily desirable to allow some air to pass around 15 the windows or doors in order that fresh air may be supplied to the interior of the building or room.

Where my device is employed, fresh air may be supplied through the secondary 20 frame and any air coming in around the window sashes will be warmed or cooled both by contact with the warm or cold secondary frame and by mixture with the warm or cold air escaping therefrom.

25 The secondary frame forms a part of the main window frame and the total cost of installation of the secondary frame is therefore reduced by the saving accomplished by the omission of the ordinary parting strips, 30 for which the secondary frame is a substitute.

It will be seen that where my invention is used, the temperature of a room may be quite accurately controlled by controlling 35 the volume and temperature of the air passing through the secondary frame.

Even in hot summer weather, when the window sashes are opened, the temperature of the room can be cooled by supplying cold 40 air from the secondary frame to the draft of air passing inwardly through the window.

By simple and suitable modifications, which are within the skill of an intelligent

workman, the installation can be modified so as to adapt it for use around a door and 45 around windows of different kinds, sizes and shapes.

The lower window sash may be provided with a metal awning or cover member 26, such as is illustrated in Figure 3, adapted to 50 cover and fit over the members 17 when the lower window sash is closed.

It is my intention to cover by the claims of my patent, any modifications in structure, which may be reasonably included within 55 the scope of those claims, and I have shown in my drawings simply an illustrative embodiment of my invention.

I claim as my invention:

1. In a device of the class described, the 60 combination of a main frame, a pair of window sashes slidably mounted therein, a tubular air conducting frame on the main frame arranged between the sashes to form parting strips therefor.

65 2. In a device of the class described, the combination of a main frame, a pair of window sashes slidably mounted therein, a tubular air conducting frame on the main frame arranged between the sashes to form 70 parting strips therefor provided with air exit openings adjacent to the path of air coming in around the sashes.

75 3. In a device of the class described, the combination of a frame, a pair of window sashes slidably mounted therein, a secondary frame of tubular material supported on said first frame and arranged to form a parting strip structure for the sashes, and including a bottom member and a cover member mounted 80 on the lower sash adapted to cover and protect the lower member of the secondary frame when the lower sash is in its lower-most position.

IRWIN H. ERB.
